Patented July 3, 1917.

Inventor:
Harry T. Thomas,
by H. T. Thomas.

UNITED STATES PATENT OFFICE.

HARRY T. THOMAS, OF BALTIMORE, MARYLAND.

DESIGN FOR A GOBLET OR SIMILAR ARTICLE.

51,003.

Specification for Design.

Patented July 3, 1917.

Application filed April 4, 1917. Serial No. 159,785. Term of patent 3½ years.

To all whom it may concern:

Be it known that I, HARRY T. THOMAS, a citizen of the United States, residing at Baltimore, in the State of Maryland, have invented a new, original, and ornamental Design for a Goblet or Similar Article, of which the following is a specification, reference being had to the accompanying drawing, forming a part thereof.

The drawing is a perspective view of a goblet showing my new design.

The central figure is a flower A having open petals, and at either side of said central

figure is placed an enlarged figure B representing a ribbon knotted or tied, each ribbon being connected to the central figure or flower by a curved line C, the whole ornamentation, which is cut in and encircles the article, having a combined flower and ribbon effect.

What I claim is:—

The ornamental design for a goblet or similar article, substantially as shown and described.

HARRY T. THOMAS.
